UNITED STATES PATENT OFFICE.

PHILIP B. HARRISON, OF CHICAGO, ILLINOIS, ASSIGNOR TO CHICAGO RAILWAY EQUIPMENT COMPANY, OF CHICAGO, ILLINOIS, A CORPORATION OF ILLINOIS.

THIRD-POINT SUPPORT FOR BRAKE-BEAMS.

1,186,092.

Specification of Letters Patent.

Patented June 6, 1916.

Application filed March 20, 1916. Serial No. 85,334.

To all whom it may concern:

Be it known that I, PHILIP B. HARRISON, a citizen of the United States, residing at Chicago, Illinois, have invented a certain 5 new and useful Improvement in Third-Point Supports for Brake-Beams, of which the following is a full, clear, and exact description, such as will enable others skilled in the art to which it appertains to make 10 and use the same, reference being had to the accompanying drawings, forming part of this specification, in which—

Figure 1 is a side elevational view partly in section of one form of my improved 15 third point support for brake beams. Fig. 2 is an enlarged detail of the form shown in Fig. 1. Fig. 3 is a modified form, and Figs. 4 and 5 are other modified forms.

This invention relates to a new and useful improvement in third point supports 20 for brake beams, the object being to provide third point supports as at present used with means whereby they are prevented from tilting or canting over the nose of the strut 25 and thereby occupying an inoperative position.

In the drawings 1 indicates the spring plank of a truck and 2 the inclined track or support mounted thereon. 30 3 is the compression member of the brake beam, 4 the strut thereof, 5 the tension member, and 6 the forwardly extending nose which is perforated to provide a pivotal support for the shoe 7 coöperating with the 35 inclined supporting track 2. The nose 6 is usually bifurcated and in order to prevent the shoe 7 from tilting upwardly and riding on the strut, in this manner occupying an inoperative position, I propose to secure 40 a projection 8 on the shoe which extends between the bifurcations of the nose of the strut and prevents the shoe from occupying

other than normal positions. In Figs. 1 and 2, this extension 8 is secured directly to the shoe; in Fig. 3 there is a face member 9 45 between the bifurcations of the strut held in position by a bolt 10 for preventing the shoe from riding the strut; in Fig. 4 the extension is secured to the bottom flange of the shoe instead of to the inside flange 50 thereof as shown in Figs. 1 and 2, the extension being given a quarter turn, and in Fig. 5 the extension 11 is secured to the bottom flange of the shoe and up along the side of the web thereof, the inner flange 55 being cut away to enable the extension to occupy its intended position.

While there may be other forms of extensions capable of use for the purposes herein described, and such other forms may 60 be secured in various ways to the shoe or third point support, I therefore do not wish to be limited to the specific forms shown as my invention comprehends the utilization of some form of separable attachment to the 65 commercial form of third point support to prevent said third point support occupying an inoperative position.

What I claim is:

A third point support for brake beams 70 comprising the combination of a strut and third point support pivotally connected thereto, and a separate projection mounted on said third point support and coöperating with a part of the beam whereby said 75 third point support is prevented from riding the strut.

In testimony whereof I hereunto affix my signature in the presence of two witnesses, this fifteenth day of March, 1916.

PHILIP B. HARRISON.

Witnesses:

M. F. HUNTOON,
E. T. WALKER.
